UNITED STATES PATENT OFFICE.

EDWIN B. BINFORD, OF PASADENA, CALIFORNIA.

MEANS FOR STAINING SHINGLES.

Application filed September 24, 1923. Serial No. 664,414.

To all whom it may concern:

Be it known that I, EDWIN B. BINFORD, a citizen of the United States, residing in the city of Pasadena, county of Los Angeles, 5 and State of California, have invented certain Improvements in Means for Staining Shingles, of which the following is a specification.

In staining shingles with creosote, or 10 other liquid, it is customary to dip a standard bundle of shingles bodily into the liquid and after letting the bundle drain a short time to place it in a machine and subject it to a rapid whirling motion whereby 15 the centrifugal action tends to distribute and throw off any surplus of liquid in the bundle, and also to throw the shingles outwardly in such a way that the bundle becomes loose and it is necessary in removing 20 the bundle from the machine to jostle them down upon a solid support to again force the shingles together so the bundle will remain intact in handling. In machines in use for this purpose there is no means provided for centering the bundle of shingles 25 over the axis of the turn table, and this causes a pounding action and also requires a stronger machine than is required where the bundle of shingles is centered over the 30 axis of revolution.

Among the salient objects of my invention are,—to provide means for holding and centering a bundle of shingles, or the like, and for whirling the same rapidly 35 about the axis of rotation, with side members capable of being moved laterally or flatwise to and from the bundle of shingles, whereby to center the same relative to the axis of the machine, which movable side 40 members can also be moved to force the shingles back into the bundle, it being possible to operate two opposite sides or walls together. These side members can be operated to open up the space to receive the 45 dipped bundle of shingles and after said bundle is placed therein, said side members can be moved toward each other, thus centering the bundle in the machine. After 50 the whirling treatment, said side members can be moved away from the bundle to afford space between the bundle and the sides or ends of the machine for picking the bundle out of the machine. Another object 55 of my invention is to provide a wall around the turn table to prevent the liquid from being thrown outwardly over surrounding

objects, said wall being provided with a top flange which operates to prevent said liquid from being thrown upwardly over the top edge of the wall. This enables me to operate the machine without a cover to be placed and removed each time the machine is operated, thus facilitating the use and operation of the machine and saving much time and inconvenience. I have also provided a clutch mechanism for quickly cutting off the power applied to the turn table whenever desired. 60 65

In order to explain my invention, I have illustrated one type of machine which embodies the same in a practical manner, which I will now describe. 70

The drawing shows a perspective view of one embodiment of the invention, with parts broken out to show the inner construction 75 and arrangement.

Referring more in detail to the drawings, I have shown a cast base with four leg portions, 1, 1, 1, 1, with a central bearing box, 2, to receive a power shaft, 3, to which is 80 keyed a drive pulley, 4, driven by a belt 5, from any suitable source of power. I have also provided a clutch, 6, adapted to be operated by a lever, 7, through the foot lever, or pedal, 8, and the connecting lever, 9, in a 85 manner which will be readily understood. A spring, 10, normally holds the clutch closed.

Secured to the upper end of the power shaft, 3, by means of a suitable head, 11, is a 90 turn table, 12, surrounded by a wall, 13, having the inturned flange, 14, substantially as shown. Secured to the turn table, 12, are two side wall members, 15, 16, shown to be bolted permanently to said turn table. Two 95 end wall members 17 and 18 are movably provided between the side members 15 and 16, said end members being provided with guide ears, as 17^a, slotted to move over guide pins, 19, set in the turn table, 12, as indicated. Said end wall members, 17 and 18, are also provided with cross bars, 20 and 21, secured thereto, with their ends extended 100 and projecting through slots, 15^a and 16^a, in the opposite side wall members 15 and 16. 105

Operating levers, 22 and 23, are pivoted to the outsides of the side wall members, as at 24, and are connected by means of links, 25 and 25', above and below the pivot 24, to the cross bars, 20 and 21, on the end wall members, as clearly indicated. Said operating levers operate in connection with quad-

rants, as 26, with latches, as 27, for holding them in adjusted positions.

From the foregoing description, in connection with the drawings, it will be seen that by operating the two operating levers, 22 and 23, together, the end wall members are moved together toward and from each other and can be so moved to center a bundle of shingles relative to the axis of the power shaft, or to force projecting shingles back into the bundle at its opposite ends.

I am aware that my invention can be embodied in many different types of machines, operated in different ways, yet getting the same result, and I have only shown the particular form thereof as a means of description. I do not, therefore, limit the invention to the showing made, except as I may be limited by the hereto appended claims.

20 I claim:

1. Means for staining shingles and the like in bundles after the bundle has been dipped bodily into a staining liquid, said means including means for rapidly whirling said bundle, manually movable means for centrally positioning said bundle relative to the axis of rotation, and means for confining the liquid thrown from said shingles during the rotating action.

30 2. Means for uniformly applying staining liquid to all shingles of a bundle after said bundle has been dipped bodily into said staining liquid, comprising a turn-table, means thereon for receiving said bundle of shingles, adjustable means for centering said bundle of shingles relative to the axis of rotation, means for driving said turn-table, and a retaining wall with inturned flange around said turn-table to confine the liquid 35 thrown from said shingles.

40 3. Means for uniformly applying staining liquid to all shingles in a bundle after said bundle has been bodily dipped into the staining liquid, said means including a turn table 45 with means for revolving the same, confining wall members to receive a bundle of shingles, some of said confining walls being adjustable toward and from each other, means for moving two walls together toward 50 and from each other, and means for holding said retaining walls in adjusted position.

4. Means for uniformly applying staining liquid to all shingles in a bundle after said bundle has been bodily dipped into the staining liquid, said means including a turn table, means for revolving the same, a confining wall around said turn table, said confining wall having an inwardly projecting flange 55 around its top edge, fixed side walls on said

turn table to receive therebetween a bundle 60 of shingles, movable end walls, means for simultaneously adjusting said end walls toward and from each other to center said bundle of shingles, and means for holding said end walls in adjusted position during 65 the revolving action.

5. In a machine of the character referred to, in combination, a turn table, means for revolving the same, a confining wall around said turn table and having an inturned 70 flange around its top edge, two fixed side walls on said turn table to receive therebetween a bundle of shingles, two movable end walls therefor, means for simultaneously moving said end walls toward and from each 75 other, and means for holding said end walls in adjusted positions.

6. In a machine of the character shown and described, in combination, a supporting base, a drive shaft therein, a driving pulley 80 thereon, a clutch for disconnecting said drive pulley from said shaft, a turn table at the upper end of said drive shaft, a confining wall around said turn table, said confining wall having an inwardly projecting flange, 85 a box-like structure mounted on said turn-table to receive therein a bundle of shingles over the axis of said drive shaft, some of said box-like wall members being adjustable toward and from each other, operating levers 90 with connections to said wall members for adjusting the same together, and holding means for holding said wall members in adjusted position during the revolving action 95 of the turn table.

7. The herein described means for uniformly distributing liquid stain over shingles in bundles, which includes adjustable means for centering and holding said bundle of shingles centrally relative to the axis of 100 rotation, means for revolving the same, and means for confining the liquid thrown from said bundle of shingles.

8. The herein means of uniformly distributing liquid stain over all the shingles 105 in a bundle, which includes means for holding and revolving said bundle of shingles, adjustable means to simultaneously force extended shingles back into the bundle endwise, and means for confining the liquid 110 thrown from the shingles during the revolution thereof.

Signed at Pasadena, Los Angeles County, California, this 17 day of September, 1923.

EDWIN B. BINFORD.
